UNITED STATES PATENT OFFICE.

THOMAS S. HOMANS, OF HEMPSTEAD, NEW YORK, ASSIGNOR TO INTERTYPE CORPORATION, OF BROOKLYN, NEW YORK, A CORPORATION OF NEW YORK.

TYPOGRAPHICAL MACHINE.

1,321,744.

Specification of Letters Patent.

Patented Nov. 11, 1919.

Application filed March 16, 1917. Serial No. 155,268.

To all whom it may concern:

Be it known that I, THOMAS S. HOMANS, a citizen of the United States, residing at Hempstead, in the county of Nassau and State of New York, have invented new and useful Improvements in Typographical Machines, of which the following is a specification.

The present invention relates to improvements in typographical machines, and more especially to those of the linotype class as shown and described in Letters Patent to O. Mergenthaler, No. 436,532. The invention is directed particularly to improvements in machines of such class whereby additional characters may be obtained from an additional magazine located at one side of the machine proper, a general arrangement of such character being shown and described in the patent to Carl Muehleisen, No. 608,067 granted July 26, 1898.

The primary objects of the present invention are to provide an improved construction and arrangement whereby the additional magazine and its coöperative parts may be easily and quickly moved to and from operative position relatively to the main machine, thus rendering the latter easily accessible for adjustments and repairs; the additional magazine and its coöperative parts will be accurately supported relatively to the main machine; simple and efficient means is provided for transmitting driving motion between the matrix delivery belt for the main machine and the additional magazine, the driving connection being preferably such that it will become operative automatically when the additional magazine is moved to operative position and will become inoperative automatically when the additional magazine is moved into inoperative position; means is provided for transferring the matrices from the matrix delivery belt for the additional magazine to the matrix delivery belt for the main machine; means is provided for accurately positioning the additional magazine in correct operative relation to the main machine; and a device is provided for moving the channel entrance for the additional magazine to and from operative relation therewith, such device also serving preferably to control the movement of the additional magazine from operative position.

To these and other ends, the invention consists in certain improvements, and combinations and arrangements of parts, all as will be hereinafter more fully described, the novel features being pointed out particularly in the claims at the end of the specification.

In the accompanying drawing:

Figure 1 is a front elevation of the right-hand portion of a typographical machine of the linotype class provided with an additional magazine and its coöperative parts in accordance with the present invention.

Fig. 2 represents an elevation of a portion of the machine as viewed from the right in Fig. 1.

Fig. 3 is a top plan view of the right-hand portion of the main machine and of the additional magazine and its coöperative parts.

Fig. 4 is a detail view, partly in section, showing diagrammatically the mode of delivering the matrices from the additional magazine to the respective delivery belt and of transferring the matrices from that belt to the matrix delivery belt of the main machine.

Fig. 5 represents a transverse section on the line 5—5 of Fig. 4.

Fig. 6 is a detail view showing the means for transmitting motion from the matrix delivery belt of the main machine to the matrix delivery belt for the additional magazine, the device being shown in operative and inoperative positions by the dotted and full lines, respectively.

Fig. 7 is a detail perspective view of a part of the motion transmitting device shown in Fig. 6.

Fig. 8 is a detail view of the device for moving the channel entrance for the additional magazine to and from operative relation therewith, and also the coöperating devices for accurately positioning the additional magazine and its related parts with respect to the main machine.

Fig. 9 represents a section on the line 9—9 of Fig. 1, looking in the direction of the arrows.

Similar parts are designated by the same reference characters in the several views.

The present invention is applicable generally to typographical machines of the type wherein type slugs are cast from lines of matrices, the latter being delivered from a magazine or magazines to form a line, and

after a cast has been made the matrices are distributed and returned to the magazine or magazines. The invention, however, is particularly adapted for use in typographical machines of the linotype class, as fully shown and described in the Mergenthaler patent above referred to. The invention in the present instance is shown applied to a machine of that type and it will be herein-
10 after so described, but it is to be understood that the invention is not restricted to the particular construction shown, as equivalent constructions are contemplated and will be included within the scope of the claims.

15 In the present embodiment of the invention, the improvements are shown applied to a plural magazine machine of the construction shown and described in my prior application, Serial No. 833,738, filed April 22, 1914.

20 For the purposes of the present invention it is sufficient to point out that 1 designates a part of the main frame of the machine, 2 designates the keyboard of the main machine, 3 designates the distributor bar which is supported by the stationary part 4 of the main frame, and M designates the upper matrix magazine, the magazines of the main machine being mounted in the manner shown and described in my prior application referred to whereby any desired magazine may be brought into operative position by manipulation of the handle 5. The matrices discharged from the magazine in use in the main machine are received by the traveling matrix delivery belt 6, this belt passing over pulleys 7 and 8 and serving to convey the selected matrices to the assembler 9. The matrix delivery belt 6 of the main machine is driven in any suitable manner such, for example, as that shown in the Mergenthaler patent referred to.

According to the present invention, the matrix distributor bar 3 is extended or has a part added thereto to form a distributor bar extension 3^a at the right-hand side of the machine, and the frame portion 4 is also extended or has a part added thereto to provide the frame extension 4^a at the right-hand side of the machine. The screws 10 which serve to feed the matrices along the distributor bar are also lengthened in order to conform to the distributor bar sections 3 and 3^a, thus enabling one set of screws to serve for the distribution of matrices to the magazines of the main machine as well as to the additional magazine. In order to accommodate the additional magazine and its co-operative parts, the frame of the main machine is provided at its right-hand side with a pair of vertically alined pivots 11 and 12, and the additional magazine and its co-operative parts are supported by a frame 13 which has bearings 14 and 15 which coöperate with the pivot pins 11 and 12, respectively. The additional magazine M' is supported on and

carried by the frame 13. Preferably, and as shown, the additional magazine is removably mounted on the frame 13 in order to permit different magazines to be used as an adjunct to the main machine. The upper 70 end of the additional magazine is adapted to receive matrices belonging to the distributor bar 3^a, an entrance 16 being provided for the purpose of directing the matrices from the distributor bar into the additional magazine. This entrance is pivoted at 17 to a bracket 18 which is attached to or forms a part of the frame of the main machine. The lower end of the additional magazine is provided with a series of escapements 19 which are adapted to be actuated by a corresponding series of reeds 20. These reeds operate under the control of a keyboard 21 which is individual to the additional magazine. The keyboard mechanism 85 for the additional magazine may be similar to that commonly used in machines of the linotype class. The keyboard is supported on and carried by the frame 13, rods 22 serving in the present instance to connect the 90 keyboard to said frame.

At the delivery end of the additional magazine is provided a matrix guide 23, this guide embodying a series of curved partitions or plates 24 which receive between 95 them the matrices dropping from the delivery end of the additional magazine and deliver such matrices upon the delivery belt 25. A cover 26 is provided for the front of the matrix guide, this cover being preferably hinged on the rod 27 to enable the cover to be swung into open position to permit access to the interior of the guide, and this rod 27 also provides a support on which the additional magazine may rest while it is 100 being applied to or removed from the frame 13, the additional magazine in the arrangement shown being applied and removed from the front of the machine. The matrix delivery belt 25 is provided in addition to 110 the matrix delivery belt 6 of the main machine, and this belt 25 is movable to and from operative position in unison with the additional magazine and its keyboard. As shown, the matrix delivery belt 25 passes 115 over pulleys 28 and 29 which are mounted on brackets attached to or formed as parts of the frame 13. When the carrier frame 13 bearing the additional magazine and its related parts is in operative position, the matrix delivery belt 25 for the additional magazine is in alinement with the matrix delivery belt 6 of the main machine, and the pulleys 8 and 28 for the respective belts are adjacent or in proximity to one another, as will appear from Figs. 1, 4 and 6. The present invention provides simple and efficient means whereby the matrix delivery belt 25 for the additional magazine is driven 120 while the additional magazine is in position 125 130

for use, and, preferably, the means provided for this purpose will operate automatically to drive the belt 25 for the additional magazine when the latter is brought 5 to operative position and it will automatically discontinue operation of the belt 25 when the additional magazine is moved out of operative position. As shown, an intermediate or idler wheel 30 is employed, this 10 idler wheel being journaled to revolve on a pivot 31 carried by a pair of arms 32, and these arms are carried by a fork 33. The fork has bearings 34 which are fitted on the pivot 35 of the pulley 28, and the fork is 15 provided with an arm or extension 36 which extends beneath the forward portion of the frame 13. A spring 37 is interposed between the arm 36 and the under side of the frame 13, and this spring acts to press the arm 36 downwardly and, in consequence, to move the power-transmitting wheel 30 into the 20 gap between the pulleys 8 and 28, the wheel 30 having a frictional engagement with the belts 6 and 25 and thereby constituting a 25 power-transmitting connection between the belts, the power being taken from the belt 6 and transmitted by the wheel 30 to the belt 25, thereby causing the belt 25 to move in unison and in the same direction with the 30 belt 6. The full lines in Fig. 1 and the dotted lines in Fig. 6 show the power-transmitting wheel 30 in operative position. To enable the operation of the belt 25 for the 35 additional magazine to be interrupted when desired, a lever 38 is provided, this lever being pivoted at 39 to the frame 13, and the lever has an offset portion 40 which is arranged to coöperate with a projection 41^a formed toward the free end of the arm 36. 40 While the power-transmitting wheel 30 is in operation, the lever 38 will occupy the position shown by the dotted lines in Fig. 6, and the spring 37 is then free to actuate the arm 36, but when it is desired to interrupt 45 the drive of the belt 25, the lever 38 is moved to the right into the position shown by the full lines in Fig. 6, the offset portion 40 of the lever riding upon the projection 41^a and thereby raising the arm 36 in opposition to the action of the spring 37, and at 50 the extreme position of the lever 38 the lever will retain the arm 36 in raised position, at which time the power-transmitting wheel 30 will occupy the inoperative position shown by the full lines in Fig. 6. This power-transmitting device between the 55 belts 6 and 25 will automatically control the operation of the belt 25 when the additional magazine is moved to and from operative position, it being understood that the axis 60 of movement of the additional magazine, which axis is coincident with the pivots 11 and 12, is offset to the rear of the belts, and hence rotating or swinging movement of the 65 magazine and its related parts about such axis will cause the belt 25 to move toward or from the belt 6, as will be clear from Fig. 3, wherein the dotted lines show the additional magazine and its related parts in inoperative position. In consequence of 70 this movement, when the additional magazine is brought to operative position, the power-transmitting wheel 30 (assuming it to be in the position shown in Fig. 1) will automatically come into contact with the 75 belt 6 and thereby establish a driving connection between the belts, and movement of the additional magazine from operative position will automatically carry the power-transmitting wheel 30 out of contact with 80 the belt 6, thereby discontinuing the operation of the belt 25. 85 The present invention also provides means for preventing movement of the additional magazine from operative position until after the entrance for the upper end of this magazine has been moved to a position where the magazine will clear it. As previously described, the entrance 16 is pivoted at 17 whereby it may occupy either the operative 90 position, as shown by the full lines in Fig. 2, or an inoperative position, as shown by the dotted lines in that figure. The entrance is shifted, in the construction shown, by a handle 41 which is pivoted to a part 95 of the frame of the main machine on an axis 42, and a link 43 is pivotally connected at its ends to the frame for the entrance 16 and the handle 41, respectively, whereby movements of the handle 41 will be transmitted to the magazine entrance. In Fig. 2, the handle 41 is shown by the full lines in its normal operative position, and the dotted lines in that figure and the full lines in Fig. 8 show the handle in the position 100 it occupies when the entrance is swung to an inoperative position. The handle 41 in the present instance provides a controlling connection between the frame of the main machine and the frame 13 which carries the 105 additional magazine. For this purpose, the handle is secured to its pivot 42 which is attached to the frame of the main machine, and it has a blade-like portion 44 which is movable to and from a position between a 110 pair of stops 45 and 46 which latter are carried by the frame 13. When the handle 41 is in its normal operative position, as shown by the full lines in Fig. 2, the magazine entrance 16 is in operative position and 115 the blade-like portion 44 of the handle occupies a position between the stops 45 and 46 of the frame 13. With the handle in this position, movement of the frame 13 in either direction about its axis is prevented. When 120 the handle 41 is moved into the position shown by the dotted lines in Fig. 2, the magazine entrance occupies an inoperative position where it will be cleared by the upper end of the additional magazine, and the 125 130

blade-like portion 44 of the handle will be out of alinement with the stop 46 on the frame 13, and the latter may then be swung to an inoperative position. It is preferable, 5 however, that the stop 45 on the frame 13 be so positioned that it will be in alinement with the blade-like portion 44 of the handle when the latter is in both operative and inoperative positions, in order that the portion 44 of the handle may serve as an abutment 10 against which the stop 45 engages when the frame 13 is swung toward the main machine to bring the additional magazine to operative position, the handle 41 and stop 45 thereby serving to limit the movement of the additional magazine toward 15 operative position. Preferably, and as shown, the stops 45 and 46 also serve to accurately position the additional magazine and 20 the matrix delivery belt 25 relatively to the magazine entrance 16 and the delivery belt 6, for which purpose set-screws are utilized for these stops as will appear from Fig. 3. When the handle 41 is in its normal position, 25 as shown by the full lines in Fig. 2, these set-screws or stops 45 and 46 will co-operate with the opposite sides of the blade-like portion 44 of the handle and the additional magazine will be accurately positioned 30 with respect to the main machine. If desired, a detent may also be employed for retaining the additional magazine and its related parts in co-operative relation with the main machine. As shown in Figs. 1 and 35 9, this detent 47 is mounted on a pivot 48 carried by a part 49 of the frame of the main machine, and the detent has a shoulder 50 arranged to engage behind one of the keyboard supporting rods 22. A spring 51 is 40 attached at one end to the detent and at its opposite end to a stationary pin 52, this spring acting to retain the detent in co-operative relation with the rod 22. Preferably, the shoulder 50 is beveled at its opposite 45 sides to enable it to act as a latch on the rod 22 as the additional magazine is moved to and from operative position, and in order to hold the detent in a position to be engaged properly by the rod 22, the detent 50 is provided with a heel 53 which is adapted 50 to rest against the pin 52 while the detent is disengaged from the rod 22.

Means is provided for insuring the proper transfer of matrices from the delivery belt 55 25 for the additional magazine to the delivery belt 6 of the main machine. Such means consists, preferably, of a conduit 54 which has a generally rectangular cross-section which bridges the gap between the adjacent 60 pulleys 8 and 28 of the belts. The top or cover 55 of this conduit is preferably curved while the bottom 56 of the conduit has an entrance portion 57 which leads tangentially from the belt 25, the bottom 65 beyond the portion 57 being formed

with a clearance recess 58 the bottom wall of which leads tangentially, or substantially so, to the belt 6. In operation, the matrices are carried along the upper stretch of the belt 25 which moves in the direction of the arrow as shown in Fig. 4, and when the matrices reach the point where the belt begins to bend around the pulley 28, such matrices are received by the tangential bottom 57 of the conduit or bridge. The inertia of the matrices causes them to pass through the conduit or bridge, and, owing to the curved form of the top wall or cover 55 of the conduit, the matrices ride or slide around the under side of this top wall, the flat side of the matrix being in engagement with the top wall, and cocking or other displacement of the matrices which might cause clogging thereof in the conduit is avoided. Preferably, the top wall or cover 55 of the conduit or bridge is removable, as shown, in order to permit access to the interior of the conduit should such become necessary. As shown in Fig. 4, the top wall 55 of the conduit is formed with laterally 90 projecting lugs 55^a to engage in undercut notches 55^b in the side walls of the conduit, and overhanging projections 55^c on the side walls are arranged to engage lateral projections 55^d on said top wall, the latter being unfastened and fastened by an endwise movement thereof relatively to the conduit. The conduit or bridge is preferably secured at 59 to the frame of the main machine, and its entrance end is arranged to 100 form a continuation of the channel 60 which is carried by the frame 13 for the additional magazine and its related parts.

According to the present invention, the main machine which comprises one unit 105 may be and preferably is a machine of the linotype class as shown and described generally in the Mergenthaler patent hereinbefore referred to, it comprising, in addition to a magazine or magazines, and matrix delivery means therefor, the necessary mechanisms for assembling the matrices, casting the slugs from the lines of matrices, and distributing the matrices after the casting operations. The auxiliary machine, constituting the other unit, provides by its magazine another font or style of matrices which the operator may use with facility as occasion may require, the matrices drawn from the additional magazine thus provided being conveyed by the respective delivery belt to the delivery belt of the main machine and thence assembled for the casting operation which takes place in the usual way in the main machine, after which the 110 matrices belonging to the additional magazine are conveyed to and properly distributed to the additional magazine by the distributing mechanism, the same being suitably adapted to this purpose.

By pivotally mounting the auxiliary machine on the main machine at one side thereof and on a vertical axis, the weight of the auxiliary machine is sustained by the main machine, the auxiliary machine is positioned accurately at the proper height to coöperate with the main machine, and the auxiliary machine may be easily swung aside to render accessible the adjacent side of the main machine when such becomes necessary. The control of the movement of the auxiliary machine to an inoperative position, according to the position occupied by the channel entrance for the additional or auxiliary magazine, avoids injury to the channel entrance or the auxiliary magazine by an attempt to shift the auxiliary machine while the channel entrance is in operative position, and the means provided for driving the matrix delivery belt from the matrix delivery belt of the main machine affords a simple and efficient drive for the delivery belt of the auxiliary machine, and it avoids unnecessary running of this belt while the auxiliary machine is not in use.

25 I claim as my invention:—

1. In a typographical machine, the combination of a plurality of composition units, each unit embodying a matrix magazine and delivery mechanism therefor, one of said units being pivotally connected on a vertical axis to the other unit and adapted to be swung into operative relation with said other unit.

35 2. In a typographical machine, the combination with a main unit supporting a magazine, coöoperative matrix controlling and delivery mechanism and matrix distributing mechanism, of an auxiliary unit embodying a magazine to coöperate with the distributing mechanism on the main unit, and matrix controlling and delivery mechanism, said units being pivotally connected whereby the auxiliary unit may swing to and from coöperative relation with the main unit and distributing mechanism thereon.

3. In a typographical machine, the combination with a main unit supporting thereon a matrix magazine, means for delivering matrices therefrom, and matrix distributing mechanism carried by and projecting laterally from the main unit, of an auxiliary unit supported on the main unit to move relatively to said main unit and said distributing mechanism in a substantially horizontal plane, the auxiliary unit embodying an additional magazine to receive matrices from the laterally projecting portion of said distributing mechanism, and matrix delivery mechanism adapted to coöperate with the matrix delivery mechanism of the main unit.

4. In a typographical machine, the combination of a plurality of relatively movable units, each unit embodying a matrix magazine and matrix delivery mechanism there-

for, matrix distributing means for such magazines, a channel entrance movable to and from coöoperative relation with the magazine of one of said units, and means governed according to the position occupied by the channel entrance for controlling relative movement between the units.

5. In a typographical machine, the combination of a plurality of relatively movable units, each unit including a matrix magazine and matrix delivery means therefor, matrix distributing means common to the different magazines, a channel entrance movable to and from coöoperative relation with one of the magazines, and means operative to shift the channel entrance and also operative to control relative movement between the units.

6. In a typographical machine, the combination of a pair of relatively movable units, each unit including a matrix magazine and matrix delivery mechanism therefor, a channel entrance shiftable to and from coöoperative relation with the magazine of one of the units, and a device for shifting said entrance, said device embodying means for retaining said units in a predetermined relation while the entrance is in operative position.

7. In a typographical machine, the combination of a pair of relatively movable units, each unit comprising a matrix magazine and matrix delivery mechanism therefor, the matrix delivery mechanism of one unit being adapted to coöperate with the matrix delivery mechanism of the other unit when said units occupy a predetermined relation, and means for positioning and retaining said units in such relation comprising a pair of stops on one of the units, and a member on the other unit movable into a position between and in coöoperative relation with said stops.

8. In a typographical machine, the combination of a pair of relatively movable units, each unit comprising a matrix magazine and matrix delivery means thereon, the matrix delivery means of one unit being adapted to convey matrices to the matrix delivery means of the other unit when the units are moved relatively to bring them into coöoperative relation, and a distributing mechanism fixed with respect to one of the units and common to the magazines of both units.

9. In a typographical machine, the combination of a main machine of the linotype class having a matrix magazine and matrix delivery means therefor, an auxiliary machine having a matrix magazine and matrix delivery means therefor, the matrix delivery means of the main and auxiliary machines being arranged at different angles, and a conduit for transferring matrices between the matrix delivery means of the main and auxiliary machines, said conduit comprising

ing a bottom wall which forms a bridge between the delivery means of the respective machines, and a curved wall located above and opposite to said bottom wall to deflect 5 the matrices as they pass from one matrix delivery means downwardly onto the other matrix delivery means.

10. In a typographical machine, the combination of a pair of units one of which 10 units is movably supported on the other unit, each unit comprising a matrix magazine and matrix delivery means therefor, the matrix delivery means of one unit being adapted to convey matrices to the matrix delivery means of the other unit, means for 15 relatively positioning said units in coöperative relation, and means arranged to be brought into driving engagement with the matrix delivery means of one of the units 20 to operate the matrix delivery means of the other unit by the relative movement of said units into coöperative relation.

11. In a typographical machine, the combination of a pair of relatively movable 25 units, one of which units is supported on the other unit to swing horizontally thereon, each unit comprising a matrix magazine and matrix delivery means therefor, the matrix delivery means of one unit being 30 adapted to convey matrices to the matrix delivery means of the other unit, and means arranged to be automatically brought into an interposed position between the delivery means of said units to drive the matrix delivery means of one of the units from the matrix delivery means of the other unit 35 when the units are brought into coöperative relation.

12. In a typographical machine, the combination of a pair of relatively movable 40 units, each unit comprising a matrix magazine and matrix delivery means therefor, the matrix delivery means of one unit being adapted to convey matrices to the matrix delivery means of the other unit, distributing 45 mechanism fixed with respect to one of the units and common to both units, and means for automatically operating the matrix delivery means of one of the units when the units are brought into coöperative relation and for discontinuing the operation of said 50 matrix delivery means when the units are relatively moved into inoperative relation.

13. In a typographical machine, the combination of a main machine and an auxiliary 55 machine pivotally supported on the main machine to swing about a vertical axis, each machine comprising a matrix magazine and matrix delivery means therefor, the matrix delivery means of the different machines being relatively movable to and from coöperative relation by swinging movements of the auxiliary machine, and driving means arranged to assume a position between the

matrix delivery means of the main machine 65 and the matrix delivery means of the auxiliary machine when the auxiliary machine is swung into coöperative relation with the main machine.

14. In a typographical machine, the combination of a pair of units movable relatively into and out of coöperative relation, each unit comprising a matrix delivery belt, 70 said belts being movable into and from coöperative relation, and means for transmitting motion from one of said belts to the other belt when the belts are in coöperative relation, said means being so located that it will assume a driving position between said belts when said units are brought into coöperative relation.

15. In a typographical machine, the combination of a main machine and an auxiliary machine movably supported thereon to move to and from operative relation thereto, each 85 machine having a matrix delivery belt, and a motion transmitting wheel adapted to occupy a position in frictional engagement with said belts when the auxiliary machine is brought into operative relation with the 90 main machine, whereby one of said belts is operable from the other belt.

16. In a typographical machine, the combination of a main machine and an auxiliary machine movably supported thereon to move to and from operative relation therewith, each machine having a matrix delivery belt, 95 said belts being relatively movable to and from operative relation by movement of the auxiliary machine relatively to the main machine, and a motion transmitting device movable into a position to drive one of said belts from the other belt when the main and auxiliary machines are brought into coöperative relation, said device being rendered inoperative 100 when the auxiliary machine is moved out of coöperative relation relatively to the main machine.

17. In a typographical machine, the combination of a main machine and an auxiliary machine movably supported thereon to move to and from coöperative relation therewith, each machine having a matrix delivery belt, a motion transmitting device for driving 110 one of said belts from the other belt, said device being automatically brought into operative position by the movement of the auxiliary machine into coöperative relation with the main machine, and means for moving said motion transmitting device into and out of position independently of the relative movement between the main and auxiliary machines.

18. The combination of a main machine 115 of the linotype class having a matrix magazine and matrix delivery means therefor, an auxiliary machine having a matrix magazine and matrix delivery means therefor,

said auxiliary machine being supported on the main machine at one side thereof by a vertical pivot and adapted to swing to and from coöperative relation with the main machine, and a distributing mechanism supported on the main machine and common to the main and auxiliary machines.

In testimony whereof I have hereunto set my hand in presence of two subscribing witnesses.

THOMAS S. HOMANS.
